SINGLE PIECE PARTITIONED CRATE

Walter F. Daley, Pelham Manor, N. Y., assignor
to Robert Gair Company, Inc., New York, N. Y.,
a corporation of Delaware

Application March 15, 1933, Serial No. 660,837

14 Claims. (Cl. 229—27)

This invention relates to containers and crates and more particularly to cardboard berry crates for shipping small berry baskets or other articles, though it is noted that in some of the claims the invention is not limited to crates for baskets or separate articles, nor even to cardboard containers.

One object of the invention is to provide an improved crate of this kind which may be shipped to the packer as a flat cardboard blank adapted to be easily and quickly erected, and closed, and secured with the baskets or articles thereof.

Another object of the invention is to provide an improved well ventilated crate of this kind which cooperates with the baskets therein to strengthen the crate.

Other objects of the invention are to improve generally the simplicity, strength and efficiency of such crates and to provide an extremely simple crate of this kind which is durable, and reliable in use, easy to pack, and economical to manufacture and ship.

Still other objects of the invention will appear as the description proceeds; and while herein details of the invention are described in the specification and some of the claims, the invention is not limited to these, since many and various changes may be made without departing from the scope of the invention as claimed in the broader claims.

The inventive features for the accomplishment of these and other objects are shown herein in connection with a berry crate which briefly stated, includes end walls foldably joining the ends of a rectangular bottom, each end wall having at each end edge a connecting flap comprising a main portion and a lower narrow extension having an upright narrow slot leaving a connecting portion adapted to be interlocked in the slot of the other extension at the same side of the bottom.

Two or more of said extensions are intermediate folded to form transverse partition members between which baskets are disposed. A horizontal partition on said members supports two horizontal rows of baskets.

A side wall joining each side of the bottom against adjacent connecting flaps carries at its free edge a cover member half the width of the bottom. Downturned tucking flaps joining the free edges of the cover members respectively are disposed face to face between said rows of baskets, and each is provided with an end notch, each end wall being slit to form a tongue adapted to be

pressed inwardly into the adjacent notches to lock the tucking flaps in place.

While in this specification and claims mention is made of materials and of the bottom, top, ends and sides of the devices and it is stated that one part is moved toward the other rather than vice versa and that parts are foldably joined by score lines, it is understood that these words are used for designation and description and that for purposes of protection they are to be construed broadly enough to cover other relative arrangements, dimensions or positions than as shown, and to cover when parts are connected by other than score lines, and in general all terms of the claims are to be given, for the purposes of protection, broad interpretation when possible.

In the accompanying drawings showing, by way of example, two of many possible embodiments of the invention,

Fig. 1 is a fragmental perspective view showing the crate partly open, this crate being adapted to hold twelve baskets;

Fig. 2 is a plan or face view showing the cut and scored unfolded blank from which the crate of Figs. 1 and 3 to 7 is erected;

Fig. 3 is a plan showing the crate with side walls still flat and unerected;

Fig. 4 is a side elevation showing the crate as in Fig. 3, with side walls unerected;

Fig. 5 is an end elevation showing the crate with one tucking flap ready to be tucked;

Fig. 6 is an end elevation showing the crate entirely closed;

Fig. 7 is a sectional view taken substantially on the line 7—7 of Fig. 6, looking in the direction of 35 the arrows of said line;

Fig. 8 is a similar horizontal sectional view showing a modified form of crate adapted to hold sixteen berry baskets; and

Fig. 9 is a fragmental perspective view of a detail of said form of Fig. 8.

My improved berry crate comprises a one piece blank (Fig. 2) cut and scored to form a rectangular bottom portion 10 and end wall portions 11 foldably joining the ends of the body portion at a 45 fold or score line 12 and adapted to be erected to form upright end walls as in Fig. 1, each end wall being provided at its top edge with a pair of slightly separated inwardly foldable cover flaps 13.

Each end wall 11 is provided at its upright end edges 15 with an inwardly turned connecting flap 16, 17, each comprising a large main inner portion 16 as high as the end wall and about half as long as the bottom portion, and an interlock-

ing extension 17 about half the height of the main portion and adapted, as will be explained, to stand against the inner face of the other main portion on the same side edge of the bottom 10. 5 Each extension is provided at its juncture with the main portion with an upright narrow slot 18 or 19 extending about half through the extension leaving a connecting portion 20, extensions 17 at the same side edge of the ends being slotted from the bottom and top edges respectively, whereby 10 the connecting portion 20 of one may be received in the slot 18 or 19 of the other as shown in Fig. 1, whereby the connecting flaps at one side edge of the bottom portion may be crossed and interlocked and both lie against the inner face of an adjacent main flap portion 16.

According to the species of Fig. 7, each of said extensions is intermediately folded on a vertical fold line 23 to form a transverse partition member 24, these members extending half across the bottom portion 10 almost into contact with similar members extending from the opposite side edge of the bottom portion, thereby forming three transverse compartments 25 each adapted 20 to receive two berry baskets 26 or the like, aiding to hold the extension 24 in place. However, the crates may be used for other articles and for material not in baskets.

If a longer crate is desired, as in Fig. 8, extensions 17' at one side, or if desired at diagonally opposite quarters of the crate may be folded and extended entirely across the plate to form long partitions 24', cooperating with a longitudinal separator 27, and an extra if desired, a separate mid-partition 27' to form eight compartments 25'. The separator 27 and said partitions are notched and interlocked as at 29, 29', Fig. 9. The remaining extensions 17'' may extend along the adjacent main portion 16 any desired distance.

The partition members 24 or 24', 27 and 27' are adapted to support a horizontal floor partition 28 adapted also to receive three or four pairs of similarly arranged baskets 26 (Fig. 6) thereon, so as to form two longitudinal rows.

A side wall portion 30 foldably joining each side edge of the bottom portion at a fold line 31 is adapted to erect to form a side wall 30 disposed against adjacent connecting flaps 16, 17, and carrying a cover member 33 foldably joining the free edge of the side wall portion and of the same length as said bottom and half the width thereof and each disposable over the adjacent longitudinal top row of baskets 26 and cover flaps.

All parts of the crate may be made of corrugated or solid fiber board or any suitable desired material.

A tucking flap 34 foldably joining the free edge of each cover member is downwardly disposable face to face with the other tucking flap, between said top rows of baskets, the tucking flaps being provided with registering end-edge notches 35 each having an upwardly faced inwardly inclined lower shoulder 36. Each end wall 11 is provided, adjacent to said notches 35 with a U-shaped slit 37 forming downwardly pointed locking tongue 8 adapted to be pressed inwardly into the adjacent notches 35 and having a blunt lower edge engageable over said inclined shoulders 36 to hold the tongues in the notches and the tucking flaps locked in place.

Said bottom portion, end walls, side walls, connecting flaps and cover members are provided with ventilating openings 40, 41, 42, 43, the openings 42, 43 of the side walls 30 and connecting

flaps 16, 17 registering with each other. The openings 40, 41 in the bottom portion, top members and end wall are round, the round openings 41 in the end walls being adapted to serve as handles for lifting the crates and for passing the fingers to the inside face of the tongues 8 to retract the latter from the notches 35.

While the cover flaps 13 ordinarily lie on top of the baskets and help to position the tucking flaps 34, it is noted that they may be turned down 10 into engagement with the notches 35 to hold down the tucking flaps if there are no baskets in the crate to position the tucking flaps in alignment with the tongues 8. Thus it is seen that the crates may, if desired, be used for material not 15 in baskets.

The blanks as in Fig. 2 may be cut from stock in staggered arrangement so as to waste little board.

The blanks may be shipped flat to the packers and quickly erected by erecting the end walls, interlocking the extensions 17 with the partitions 24 disposed inward. Then the baskets are put in place, as in Fig. 6, the cover flaps 13 bent over as in Fig. 3, the side walls brought up and 25 the tucking flaps tucked in as in Fig. 5; and then the tongues 8 are pushed into the notches 35. The crate may be unfolded in reverse manner.

The crate is inherently strong and durable; and the baskets, tucking flaps 34, connecting 30 flaps, and partitions 24 all cooperate to increase the strength, so that the durability of the crate in shipping is great.

I claim as my invention:

1. In combination, a crate comprising a bottom; end walls joining the ends of the bottom, each having at its end edges a connecting flap each having a lower extension interlocked with an adjacent extension at the same side of the bottom; transverse partition-forming members 40 on said adjacent extensions and infolded across said bottom; a side wall joining each side of the bottom exterior to and against adjacent connecting flaps; a cover member joining the side wall of half the width of the bottom; a downturned 45 tucking flap joining each cover member; and means holding the tucking flaps in place.

2. A berry crate comprising a one piece blank cut and scored to form a rectangular bottom portion; end wall portions foldably joining the 50 ends of the body portion and adapted to be erected to form upright end walls, each provided at its top edge with a pair of slightly separated inwardly foldable cover flaps; each end wall being provided at each upright end edge with an 55 inwardly turned connecting flap, each comprising a large main portion as high as the end wall, and about half as long as the bottom portion, and an interlocking extension about half the height of the main portion and adapted to lie 60 against the inner face of other main portion at the same side of the bottom and provided at its juncture with the main portion with an upright narrow slot extending about half through the extension leaving a connecting portion, adjacent 65 extensions being respectively slotted from the bottom and top edges, whereby the connecting portion of one may be received in the slot of the other, whereby the connecting flaps at one side edge of the bottom portion may be crossed 70 and both lie against the inner face of the adjacent main flap portion; each of said extensions being intermediately folded on a vertical fold line to form transverse partition members; a side wall joining each side of the bottom por- 75

- tion exterior to and against adjacent connecting flaps; a cover member joining the side wall of half the width of the bottom; and means holding the cover members in place.
5. A crate comprising a bottom; and end walls joining the ends of the bottom, each having at its end edges a connecting flap each having a lower extension interlocked with an adjacent extension at the side of the bottom; said extensions being intermediately folded to form a transverse partition member extending half way across said bottom; and a horizontal floor partition on the members.
10. A crate comprising a bottom; end walls joining the ends of the bottom; each having at its end edges a connecting flap each having a lower extension interlocked with an adjacent extension at the side of the bottom; a side wall joining each side of the bottom exterior to and against adjacent connecting flaps; a cover member joining the side wall of half the width of the bottom; a down-turned tucking flap joining each cover member; each extension being inwardly folded to form transverse partition member almost into contact with similar members extending from the opposite side edge of the bottom portion, thereby forming three transverse compartments each adapted to receive two baskets aiding to hold the extension in place.
15. A crate comprising a bottom; and end walls joining the ends of the bottom, each having at its end edges a connecting flap each having a lower extension interlocked with an adjacent extension at the side of the bottom; one or more of said extensions being intermediately folded to form a transverse partition member extending entirely across the bottom.
20. A crate comprising a bottom; end walls joining the ends of the bottom, each having at its end edges a connecting flap each having a lower extension interlocked with an adjacent extension at the same side of the bottom; each of said extensions having a transverse partition-forming member thereon, said partition-forming members being transversely infolded across said bottom and a side wall joining each side of the bottom exterior to and against adjacent connecting flaps; said side walls and flaps having registering ventilating openings.
25. In combination, a crate comprising a bottom; end walls joining the ends of the bottom, each having at its end edges a connecting flap; each flap having a lower extension interlocked with an adjacent extension at the side of the bottom; transverse partition-forming members on said adjacent extensions and transversely infolded across said bottom; a side wall joining each side of the bottom exterior to and against adjacent connecting flaps; a cover member joining the side wall of half the width of the bottom; a down-turned tucking flap joining each cover member; separated, inwardly foldable cover flaps on the ends of said end walls adapted to engage and hold said cover tuck flaps; said bottom, end walls, side walls, connecting flaps and cover members being provided with ventilating openings, the openings of the side walls and connecting flaps registering with each other; the openings in the bottom portion, end walls and top members being round, the round openings in the end walls being adapted to serve as handles for lifting the crates.
30. A crate comprising a bottom; end walls joining the ends of the bottom; each having at its end edges a connecting flap each having a lower extension interlocked with an adjacent extension at the side of the bottom and inwardly bent to form partition members; a side wall joining each side of the bottom exterior to and against adjacent connecting flaps; a cover member joining each side wall and of half the width of the bottom; a horizontal floor partition on said partition members adapted to receive three pairs of baskets thereon; side wall portion foldably joining each side edge of the portion and adapted to be erected to form a side wall disposed against adjacent connecting flaps; a cover member foldably joining the side wall portion, of the same length as said bottom and half the width thereof and each disposable over the adjacent longitudinal top row of baskets; and a tucking flap foldably joining the free edge of each cover member, the tucking flaps being disposable face to face between said rows.
35. A crate comprising a bottom; end walls joining the ends of the bottom; a side wall joining each side of the bottom; a cover member half the width of the bottom joining the free edge of each side wall; downturned tucking flaps joining the free edge of the cover members respectively and disposed face to face with each other and each provided with an end notch; each end wall being slit to form a tongue adapted to be pressed inwardly into the adjacent notches, the end walls having holes adjacent to the tongues for inserting a finger to press the tongue outwardly.
40. A crate comprising a bottom; end walls joining the ends of the bottom; a side wall joining each side of the bottom; a cover member half the width of the bottom joining the free edge of each side wall; and downturned tucking flaps joining the free edge of the cover members respectively and disposed face to face with each other and each provided with an end notch; each end wall being slit to form a tongue adapted to be pressed inwardly into the adjacent notches.
45. A crate comprising a bottom; end walls joining the ends of the bottom; each having at its end edges a connecting flap each having a lower extension interlocked with an adjacent extension at the side of the bottom; a side wall joining each side of the bottom exterior to and against adjacent connecting flaps; a cover member joining the side wall of half the width of the bottom; downturned tucking flaps joining each cover members and provided with registering end-edge notches each having an upwardly faced inwardly inclined lower shoulder; said end walls being provided, adjacent to said notches with U-shaped slits and openings adjacent thereto, each slit forming a downwardly pointed locking tongue adapted to be pressed inwardly into the adjacent notch and having a blunt lower edge engageable over said shoulders to hold the tucking flaps locked in place.
50. A blank for making crates, said blank being blank-cut and scored to form a bottom; end walls joining the ends of the bottom; a side wall about as wide as the end wall, joining each side of the bottom; a cover member as long as said bottom and about half the width thereof joining the free edge of each side wall; and a tucking flap joining the free edge of each cover member and each provided with an end-edge notch; each end wall being slit to form a locking tongue having an inwardly faced free edge about as distant from the outer edge of the end wall as the notch is from the cover member.
55. A one piece blank for making berry crates said blank being blank cut and scored to form a

rectangular bottom portion; end wall portions foldably joining the ends of the body portion; each provided at its free edge with a pair of slightly separated foldable cover flaps; each end wall portion being provided at each end edge with a connecting flap, comprising a main portion as wide as the end wall portion, and about half the length of the bottom portion, and an interlocking extension about half the width of the main portion and provided at its inner end with a transverse slot extending about half through the extension, said slots of adjacent extensions opening at opposite edges, and each having an intermediately transverse fold line; a side wall portion, as long as the bottom portion and about as wide as the end wall portion, foldably joining each side edge of the bottom portion; a cover member of the same length as said bottom and half the width thereof, foldably joining the free edge of side wall portion; a tucking flap foldably joining the free edge

of each cover member and each provided with an end-edge notch each having an inwardly inclined lower shoulder faced away from the free edge of the flap; each end wall being provided with U-shaped slit forming an inwardly pointed locking tongue having a blunt free edge about the same distance from the outer edge of the end wall that the notch is from the inner edge of the tucking flap.

14. A crate comprising a bottom; end walls 10 joining the ends of the bottom, each having at its end edges a connecting flap each having an extension interlocked with an adjacent extension at the side of the bottom; one or more of said extensions being intermediately folded to form a trans- 15 verse partition member extending entirely across the bottom and provided with a transverse slot therein; and a longitudinal separator interlocked in said slots.

WALTER F. DALEY. 20
